UNITED STATES PATENT OFFICE.

AUGUSTUS HAGER BRYANT, OF GLEN RIDGE, NEW JERSEY.

SAFETY-RAZOR BLADE.

1,309,456.

Specification of Letters Patent.

Patented July 8, 1919.

Application filed November 26, 1918. Serial No. 264,180.

To all whom it may concern:

Be it known that I, AUGUSTUS H. BRYANT, a citizen of the United States, and a resident of Glen Ridge, in the county of Essex 5 and State of New Jersey, have invented a new and Improved Safety-Razor Blade, of which the following is a full, clear, and exact description.

This invention relates to safety razor 10 blades and has for an object the provision of an improved construction wherein a very high grade blade may be produced having overhanging shoulders.

Another object in view is to provide a 15 safety razor blade of high grade material with a back mounted thereon formed with an extension projecting beyond each end so as to produce shoulders for the blade.

In the accompanying drawing:

20 Figure 1 is a front view of a blade disclosing an embodiment of the invention.

Fig. 2 is an edge view on an enlarged scale of the blade shown in Fig. 1.

25 Fig. 3 is a section through Fig. 1 on line 3—3, the same being on an enlarged scale.

Fig. 4 is a view similar to Fig. 1, but showing an old construction.

In the construction of safety razor blades some are made with apertures for receiving 30 guiding pins which hold them in place while the clamp is being adjusted. In other forms of safety razors projections are provided as shown in the old blade indicated as 1 in the drawing. This blade is provided with projections or ears 2 and 3 formed integral with the blade 1. It will be observed that the blade 1 is ground with an irregular edge 4 and is honed with an additional irregular cut 5. The reason of this irregular sharpening is by reason of the fact that the blade is necessarily sharpened by hand manually 35 and it is physically impossible for the operator to hold the blade perfectly true against the grinding or honing device. This form of blade is stamped out of a ribbon of soft steel, is then hardened and finally ground and honed. It is necessary to form these blades from the soft material in order to secure the right shape by stamping them out 45 by the use of dies so that it is necessary to temper the blades either individually or in packs. In either instance the blade will be more or less unevenly tempered; and also some blades will be hardened to a greater 50 extent than others. In addition the blades being necessarily cut out while soft and then hardened, the sharpening operations are carried on manually with one blade at a time. These manual operations during the sharpening actions cause the irregular or 55 uneven sharpening cuts 4 and 5. To obviate this more or less undesirable feature of manually grinding the blade and the undesirable feature of the particular way in which the blade is tempered a new structure 60 is provided according to the present invention in which a blade 6 is used. This blade is formed from a ribbon of uniformly high tempered steel, and a steel hardened to a greater extent than blade 1 whereby the 65 edge 7 will remain sharp for a greater length of time. Before breaking the ribbon into proper blade lengths the ribbon is passed through an automatic machine which grinds an even bevel and true edge for the 70 entire length of the ribbon, this furnishing a proper base for the finishing or stropping device which provides a very even, smooth and uniformly fine cutting edge. The ribbon is then placed in a breaking machine 75 and broken off into lengths after which the back 8 is pressed thereon by any desired means, as for instance a hydraulic press. This back tightly grips the back edge of the 80 blade 6 so that it cannot be removed under ordinary circumstances. A back arranged in this manner not only affords stiffening means for the blade, which is extremely thin, and shoulders for holding the blade 85 properly in position in the holder, but acts 90 by reason of its thickness as means for guiding the blade properly through honing and stropping machines. If it was attempted to feed thin blades without backs through either of these machines the blades would 95 overlap and jam, and by providing a back which is appreciably thicker than the blade the various blades may be lined up tandem fashion and passed through the grinding and honing machine in such a manner as to 100 be properly acted upon. The back is preferably perfectly straight so as to hold the cutting edge at the exact height to be properly operated on by the honing and also by the stropping machine while the thickness 105 of the back causes the rear blades to easily push the front blades and in that manner cause a continuous string to pass through the two machines just mentioned. In addition to forming a back for the blade 6 it is 110 made sufficiently long to provide shoulders 9 and 10, said shoulders if desired being

rounded on the outer ends for producing a more finished appearance. These shoulders form projections which will act similar to projections 2 and 3 when the blade is in use—namely: as retaining members coacting with the holder. In the particular form of holder adapted for blades with extending shoulders upstanding lugs or stops are provided so as to engage the shoulder and limit the movement of the blade toward the guarding fingers, whereby the edge is always in the right position when the shoulders engage the stop.

By this method of forming a safety razor blade a very high grade of steel may be used as well as a very hard product. In addition the edge 7 is produced by a grinding machine acting on the entire length of the ribbon of steel instead of the manual grinding necessary in the structure shown in Fig. 4. Preferably the blade 6 is also made thinner than blade 1 as it is supplied with a stiffening back 8. The extensions or shoulders 9 and 10 act exactly in the same capacity as extensions or ears 2 and 3 so that the addition of the back 8 really accomplishes two purposes, namely presents a stiffening structure and presents shoulders acting as a substitute for the integral shoul-

ders 2 and 3. During the act of pressing the back 8 in position on the blade 6 the ends 9 and 10 are pressed together as shown in Fig. 2 so as to make a neat construction and also act as an additional pinching means for the blade. This will also positively prevent any longitudinal movement of the blade in case it should become loose which is substantially impossible though the back is put on cold.

What I claim is:

1. A razor blade comprising a blade structure having one sharpened edge, a back substantially U-shaped in cross-section clamped to the opposite edge of said blade structure, said back projecting beyond the ends of the blade structure, said projecting portions being pressed together.

2. A razor blade comprising a rectangular shaped blade body formed of very hard stiff steel sharpened along one of its longitudinal edges, and a back thicker than the blade formed with a substantially U-shaped straddling portion clamped to the opposite edge, and with projecting shoulders extending beyond the ends for producing retaining means when the blade is in a holder.

AUGUSTUS HAGER BRYANT.
